US0D1055030S

(12) **United States Design Patent** (10) **Patent No.:** **US D1,055,030 S**
(45) **Date of Patent:** **** Dec. 24, 2024**

(54) **EARPHONE**

(71) Applicant: **Panasonic Intellectual Property Management Co., Ltd.**, Osaka (JP)

(72) Inventor: **Yosuke Nakamura**, Osaka (JP)

(73) Assignee: **PANASONIC INTELLECTUAL PROPERTY MANAGEMENT CO., LTD.**, Osaka (JP)

(**) Term: **15 Years**

(21) Appl. No.: **29/882,741**

(22) Filed: **Jan. 18, 2023**

(30) **Foreign Application Priority Data**

Aug. 3, 2022 (JO) ..... 2022-016597 D

(51) **LOC (14) Cl.** **14-01**

(52) **U.S. Cl.**

USPC **D14/223**

(58) **Field of Classification Search**

USPC D14/223, 205; D24/106; 381/322, 325, 381/328, 330

(57) **CLAIM**

The ornamental design for an earphone, as shown and described.

DESCRIPTION

FIG. 1 is a perspective view of an earphone showing my new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a rear elevational view thereof.

The broken lines in the drawings illustrate portions of the earphone that form no part of the claimed design. The dash-dotted lines in the drawings define the boundaries of the claimed design.

1 Claim, 7 Drawing Sheets
